UNITED STATES PATENT OFFICE.

JAMES B. BREWSTER, OF NEW YORK, N. Y.

AMALGAMATOR.

SPECIFICATION forming part of Letters Patent No. 441,089, dated November 18, 1890.

Application filed September 12, 1889. Serial No. 323,757. (No model.)

To all whom it may concern:

Be it known that I, JAMES B. BREWSTER, a citizen of the United States, residing at the city of New York, in the county and State of New York, have invented a new and useful Improvement in Amalgamators, of which the following is a specification.

My invention relates to that class of amalgamators in which mercury is used to extract precious metals from the various impurities combined with them in the ores in which they are found, and has for its primary object the working of ores of a friable or semi-fluid sticky nature—such, for instance, as some of the adhesive muds in which gold is found.

The nature of the invention consists in the details of combination and construction, substantially as illustrated in the accompanying drawings hereinafter described, and subsequently pointed out in the claim.

Figure 1 is a side view of my amalgamator. Fig. 2 is a top view of the same. Fig. 3 is a front view of the same. Fig. 4 is a longitudinal vertical sectional view of the same. Fig. 5 is a detail view of a pocket more fully hereinafter described.

A A designate the body of the machine. From this slopes away the stepped incline B. Within the body of the machine at one side is placed a deep narrow vertical pocket, (designated by I.) This pocket is made fast to the body of the machine, is made water-tight, the outer edge a a little higher than the inner edge b, and may be formed of any suitable material. Iron, however, seems preferable.

C designates a division-board, which is held in position in said pocket by two grooves, one in each end of said pocket, into which the edges of said board slip, so that it can be put into or taken out of said pocket at pleasure. Upon the top of this board in suitable bearings is journaled the shaft D. Upon this shaft are mounted the pulley E and the lantern-drum E'. A series of endless chains (designated by G) pass over this lantern-drum E' and around the board C, so that it can be placed with said board in said pocket I, as illustrated in the drawings, and the said shaft, pulley, lantern-drum, chains, and board all so arranged and connected that when said board is removed from said pocket they will all be removed together with it. The pipes

F F are adapted to cast a spray of water into this pocket. From the inner and lower side d of this pocket an inclined screen (designated by H) extends across the body of the machine to an opening H' in the opposite side. Directly under this screen is the amalgamating-table K, which may be nearly horizontal. A slot k in the side wall of the machine gives communication between this table and the stepped incline B. The surface of this table and the surface of the stepped incline should both be covered with amalgamating-plates. The plates on the incline 65 are preferably corrugated. At the foot of the incline is another pocket, (designated by L.) This pocket is so arranged that it communicates with the bottom step of the incline. The outer edge of the pocket is the lowest. The 70 inside of this pocket is faced with amalgamating-plate. Within this pocket is a removable partition, (designated by M.) To the bottom edge of this partition is fastened a bar, (designated by m.) A water-pipe n passes 75 through this partition from edge to edge and communicates with another water-pipe o, which is parallel with the under side of said partition and between the bottom of said partition and said bar m. Proper orifices in said 80 pipe o allow the water to spurt in jets into said pocket.

The body of said machine may be made of wood or any other suitable material. A belt on the pulley E may connect the machine 85 with any suitable motor. A hopper (designated by P) may be placed on the pocket I, as illustrated, to assist in manipulating the machine.

To use this amalgamator quicksilver in the 90 required quantity is deposited in the pocket I, and also in the pocket L, until it covers the lower edge of the bar m. Water under pressure is let on through the above-mentioned pipes and the shaft set in motion by a belt on 95 the pulley, as before described. Friable or muddy sticky ore is now fed through the hopper P into the outside part of the pocket I and against the chains G. The ore, partly by its own weight and partly by the motion of 100 the chain G, is carried downward toward the bottom of the pocket, being broken, crushed, and comminuted as it goes down. When it reaches the bottom of the pocket, it passes

through the mercury and under the division-board. Here the larger and free pieces of precious metal will be dropped in the bottom of the pocket; but the lighter particles, many of which contain precious metal, will be carried upward on the inner side of the division-board between it and the wall of the pocket. The motion of the chains rubbing on the board will wash, scour, and brighten the particles of precious metal still in the ore, so that when they reach the top of this side of the pocket and passing over the edge fall upon the screen H, the clean bright surfaces of metal which they present will be very easy to amalgamate, so that when it comes to pass over the amalgamating-surfaces, as hereinafter described, but little of the precious metal will fail to be amalgamated and but little of it pass off in the tailings.

At any time it is necessary the board and its accompanying mechanism may be removed from the pocket. It will then be much easier to wash and clean, and the pocket, too, being empty, will be much easier to wash and clean. The larger pieces roll down the screen and out of the machine through the opening H'. The finer portions fall through the screen on the table K and make their way through the slot k to the stepped incline, down which they make their way to the pocket L. Thus far the material has been carried by the action of the water flowing from the pipes in the bottom of the pocket I; but when it comes into the last pocket L the water flowing into that pocket carries it down

through the mercury, under the bar m, and out through the pocket over the outer and lower edge and out of the machine. As the pulp passes through the machine, the larger pieces of gold are deposited along the track of the pulp and the smaller pieces are amalgamated by the mercury, so that but little of the gold or other precious metal escapes out of the machine with the gangue.

What I claim as my invention, and desire to secure by Letters Patent, is—

An amalgamator for precious metals, consisting of an upright pocket provided with a groove in the inside of each end wall, a removable division-board fitting into said grooves, a shaft journaled upon the upper edge of said division-board, a pulley and drum mounted on said shaft, a series of endless chains upon said drum and surrounding said division-board in said pocket, said division-board, pulley, drum, and chains being all attached as hereinbefore described, whereby they may be together removed from said pocket, in combination with suitable amalgamating-surfaces arranged at the discharge side of said pocket, all substantially as and for the purpose set forth.

In testimony that I claim the foregoing as my invention I have signed my name in presence of two witnesses.

JAMES B. BREWSTER.
